UNITED STATES PATENT OFFICE.

GEORGE S. BARKENTIN, OF NEW BRITAIN, CONNECTICUT, ASSIGNEE TO
P. & F. CORBIN, OF SAME PLACE.

DESIGN FOR A DOOR-KNOB.

SPECIFICATION forming part of Design No. 17,339, dated May 10, 1887.

Application filed March 21, 1887. Serial No. 230,778. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for a Door-Knob, of which the following is a specification, reference being had to the accompanying drawings, forming part thereof.

10 Figure 1 is a front elevation of my newly-designed door-knob, and Fig. 2 is a side elevation of the same.

A designates the knob-shank, and B the knob. At the junction of the knob and shank 15 there is on said shank, as seen in side view, Fig. 2, a plain band, 1, then a rounded bead, 2, extending into a groove on the knob side. From this groove the profile of the knob shows an ogee, 3, and extending from the highest part 20 thereof over the side of the knob is a large rounded bead, 4, having a groove, 5, at the summit, ornamented by a series of small rounded projections, 6. Rising from the front side of the bead 4 is another bead, 7, while the end 25 of the knob is the ornamental front face. Its general form is rounded out slightly from the bead 7 and then inward, forming a concavity with an ornamental central boss, 8, as shown in Fig. 1 and as indicated by broken lines in 30 Fig. 2.

The ornamental front face is clearly shown in Fig. 1. The ornamental central rounded knob or boss, 8, is marked by short lines inter-

secting in reticular form. Surrounding this boss there is a narrow annular face marked by 35 radial lines. The remainder of the front face is mainly ornamented by leaflets and scroll-work, as shown.

I claim—

1. The design for a door-knob herein shown 40 and described, the same consisting of the front face having the concavity with the central boss, 8, with reticular lines on the surface of said boss.

2. The design for a door-knob herein shown 45 and described, the same consisting of the front face having the concavity, with the central boss, 8, marked by reticular lines and the surrounding narrow annulus marked by radial lines.

3. The design for a door-knob herein shown 50 and described, the same consisting of the front face having the central boss, the surrounding narrow annulus, while the surface outside said annulus is mainly ornamented by leaflets and scroll-work, and the plain bead 7 forming a border for said face.

4. The design for a door-knob herein shown 55 and described, the same consisting of the front face and peripheral sides having the several beads, groove 5, and series of rounded projections 6 in said groove.

GEORGE S. BARKENTIN.
